UNITED STATES PATENT OFFICE

129,281

DESIGN FOR A PROTECTIVE MAT FOR KITCHEN TABLES, STOVES, AND THE LIKE

James R. Caldwell, Wooster, Ohio, assignor to
The Wooster Rubber Company, Wooster, Ohio

Application June 18, 1941, Serial No. 101,531

Term of patent 7 years

To all whom it may concern:

Be it known that I, James R. Caldwell, a citizen of the United States, residing at Wooster, in the county of Wayne and State of Ohio, have invented a new, original, and ornamental Design for a Protective Mat for Kitchen Tables, Stoves, and the like, of which the following is a specification, reference being had to the accompanying drawing, forming part thereof, wherein:

Figure 1 is a plan view of a protective mat for kitchen tables, stoves and the like, embodying my new design.

I claim:

The ornamental design for a protective mat for kitchen tables, stoves, and the like, substantially as shown.

JAMES R. CALDWELL.
